UNITED STATES PATENT OFFICE.

JAMES McCALLUM, OF CHICAGO, ILLINOIS.

IMPROVEMENT IN WAGON-RACKS.

Specification forming part of Letters Patent No. 222,415, dated December 9, 1879; application filed February 4, 1879.

To all whom it may concern:

Be it known that I, JAMES McCALLUM, of the city of Chicago, county of Cook, and State of Illinois, have invented a new and useful Improvement in Wagon-Racks, of which the following is a specification.

The invention relates to arms, brackets, and sockets to be applied in the construction of wagon-racks, in manner hereinafter described.

Heretofore such racks have been made separate from the wagon-box, and when required for use the box had to be removed, requiring extra help, taking up room for storage when not in use, and the rack, being open at the bottom, allowed grain that shelled out in handling to fall through to the ground and become wasted, all of which is saved by my improvement.

Other devices have been made to be attached to the box of the wagon; but the short brackets split the box, and the arms, having to be spliced with wood, were unwieldy, weak, and expensive.

The object of my invention is to provide a system or combination of arms, brackets, and sockets so constructed that the arms can be shifted into different positions, and thereby of themselves afford the different kinds of racks and top boxes, that would otherwise have to be made separately and at considerable expense, and when so made are not as strong and cheap as mine.

The socket piece or bracket B in Figure 2 extends the whole depth of the box, and, passing through the cross-piece at the bottom, is firmly bolted, and forms a strong support to the box itself.

The arm A, as shown in Fig. 1, is composed of malleable iron or other suitable material, is about two feet long, is punctured with holes for bolting thereon strips of board or other material. The base or foot *i* of the arm is about seven inches in length, the whole length of which is inserted in the socket piece or bracket B, as shown in Fig. 1. The part *j* of this arm A is also fitted on its upper side to fit into the socket of the bracket B, as shown in Fig. 2. The arm A is preferably strengthened by a web, *m*.

In the accompanying drawings, in which similar letters of reference indicate like parts,

Fig. 1 is a perspective of the arm A, with its base *i* fitted into socket *c* of the bracket B so as to produce the foundation for a hay, straw, or similar rack, requiring a broad surface to load upon. The arm is so constructed that when so inserted it gives the proper incline for a broad rack. A rack composed of ten of these arms, four on each side and two on the rear end of the box, will sustain a weight of four thousand pounds.

The socket may be square, as at *c*, Figs. 1, 2, 3; or rounded or oval, as at *d*; or acute-angled at its corners *f f*; and in either case adapted for dovetailing with the corresponding part *i* or *j* of arm A.

Fig. 2 is a view of the arm A inserted in the socket C or D of the bracket in an upright position, the top of the flanges of base *i* of the arm A being cut away, as shown at *l*, to permit the flanges K to fit in the socket after the manner shown in Fig. 1; but for the purpose of producing an upright hog or corn rack or top box the forming of this arm A so that it can be shifted into either of the above-described positions without removing the boards or strips that are bolted thereon, together with the construction of a bracket B, provided with oval or square or angular open sockets, as shown in Figs. 3 and 4, embodies the essential feature of my invention. Fig. 3 shows a top view of bracket B, with the square socket. Fig. 4 shows a top view of bracket B, with the oval socket, and both or either of these may be used by me in construction of the arms and brackets. Fig. 5 gives a perspective view of my header-box, as constructed for the States and Territories west of the Rocky Mountains, where it is customary to harvest the heads of grain only. I make this box by closing the surface E of the hay-rack, and by passing around the outer edge an upright board, F, of sufficient height, which is fastened in place by means of bolts with a clip on the bottom, which is fastened to the end of the arm A. I use standard G, Fig. 6, for light top boxes, the base of the standard being formed to fit the sockets, which may be used, as before stated, when a light and narrow top box is desired.

It will now be seen that the following are some of the advantages due to my improvements, viz: The devices can be readily ap-

plied to any wagon and by any inexperienced person; the wagon body or box need not be lifted off to adapt it for the various uses for which different kinds of racks are needed; that the same arms serve either for vertical or horizontal racks, and the same brackets also serve for both positions of the arms without need of change or removal of the brackets, thus insuring great economy, and combining this economy with simplicity and wide utility.

I claim—

1. The wagon-rack arm A, constructed, substantially as described, with flanges at its base

and at its side, whereby it may be inserted in the same bracket either in an upright or in a horizontal, or nearly horizontal, position, for the purposes set forth.

2. The combination of the arms A, constructed for use in the two positions, as shown and described, with the dovetailed socketed brackets B, as set forth.

JAMES McCALLUM.
